UNITED STATES PATENT OFFICE.

MYRICK DUDLEY, OF LYNN, MASSACHUSETTS, ASSIGNOR OF TWO-THIRDS
TO IVORY B. HILL, OF TAMWORTH, NEW HAMPSHIRE.

RAILWAY-SWITCH.

SPECIFICATION forming part of Letters Patent No. 374,827, dated December 13, 1887.

Application filed September 13, 1886. Serial No. 213,385. (No model.)

To all whom it may concern:

Be it known that I, MYRICK DUDLEY, of Lynn, in the county of Essex and Commonwealth of Massachusetts, have invented certain 5 Improvements in Street-Railway Switches, of which the following, taken in connection with the accompanying drawings, is a specification.

This invention relates to means for working the switches of railways, and the nature thereof is fully described and specifically claimed hereinafter.

Figure 1 is a perspective view of a car-truck, a portion of the platform being broken away to show the operating mechanism. Fig. 2 is 15 a perspective view of a detached portion of the mechanism.

In this invention I make use of a switch-bar, A, that is provided with a cross plate or bar, a, on which are the upwardly-projecting pieces 20 or lugs b c. Said parts may be constructed integral with the bar A, or may be separately formed and secured thereto. In all other respects the rails are the same as now in common use.

25 The mechanism designed for operating the switch A is represented, mainly, in the second figure of the drawings. It comprises the bar B, on which are fixed the downwardly-projecting feet or bosses e f, the operating-lever D, provided with swiveled fulcrum h and handle 7. These parts are attached to the car, as fully 30 shown in Fig. 1. For the purpose of attaching these parts to the car I employ plates E, Fig. 1, which are secured to the car-axle boxes, and said plates are provided with heads F, 35 having slots 4, adapted to receive the ends of bar B. Said bar is arranged in said slots, as shown, and permits vertical movement, to the end that it may be lifted so as to raise the feet e f high above the rail whenever occasion 40 requires. The bar also permits lateral or end-wise movement, to the end that it may be moved to carry the feet e or f, as occasion requires, into line for engaging the projections b or c 45 and moving the switch-bar A. The bar B is operated by the workman through the instrumentality of the lever D. To this end the lever D is secured, by means of the plate k, to the bottom of the car-platform, as shown, thereby 50 forming a swiveled fulcrum for the suspended

lever. The rear end of said lever is connected, as shown, with a pin, 6, which is secured in the bar B. The forward end of said lever extends forward and upward, terminating, as shown, in a handle, 7. The bar B, when idle, is depressed by its own gravity, as represented in Fig. 1. The feet e f are then in line with and just above the rail and operate as a fender to remove any small obstructions that may be on the rail. In operation the foot e or f, as occasion requires, is brought into line for engaging the projections b or c, as occasion requires, and thereby carrying the switch-bar into position, as required, to give the desired direction to the car.

In Fig. 1 the foot f is in position to engage the projection b and switch or move the bar A, so as to permit the car to turn the curve; but suppose the bar A were out of line with the straight rail, and yet it might be desirable to 55 send the car along the straight rails. In this case the foot would be shifted into position to engage the projection c and move the bar A into line with the rail. These various movements of the bar B to position the feet e and f 60 are effected by the workman, who grasps the handle 7, depresses the lever D, thereby lifting it out of a notch in the car-platform, (not shown,) and then moves it to the right or left, as occasion requires, to give the desired movement to the 65 bar B. This being gained, the handle is released. The lever D is then lifted by gravity of bar B, and the end of the lever D, falling into a slot or over a pin in the car-platform, is secured 70 from further movement until the switch-bar 75 is passed.

The projections b c, it will be observed, are beveled or inclined in one direction. This is done to the end that the feet e f may be lifted and pass over the projections when the car 80 travels in the opposite direction.

It should also be observed that the end of lever D is connected with bar B by means of a pin, 6, the lever being allowed free movement along the pin, as shown, to the end that these 85 parts may not be cramped and broken by the rocking movements of the car.

I claim—

1. In a railway-switch, and in combination, the switch-rail A, provided with one or more 90

projections, the bar B, provided with feet *e f*, said feet being rigidly attached to the bar which extends from side to side of the car, and the lever D, for operating the bar, substantially as described.

2. In combination, the switch-rail, the bar B, arranged transversely of the car and having the feet *e f* secured thereto and supported thereby, the said bar having vertical and transverse movement, and the operating-lever D, all substantially as described.

3. In combination, the bar B, having feet *e f*, the operating-bar D, and the switch-rail provided with projections, said projections being

formed with a beveled edge upon one side, 15 substantially as described.

4. In combination, the bar B, provided with the downwardly-projecting feet *e f*, the supporting brackets F, provided with grooves or slots 4, and mechanism for operating the bar 20 B, substantially as described.

5. The combination of the lever D, provided with handle 7, the bar B, and pin 6, all substantially as set forth.

MYRICK DUDLEY.
